UNITED STATES PATENT OFFICE.

RAYMOND C. DUDLEY, OF CHICAGO, ILLINOIS.

CAR-ROOF.

1,133,372.

Specification of Letters Patent. Patented Mar. 30, 1915.

Application filed September 18, 1909. Serial No. 517,366.

To all whom it may concern:

Be it known that I, RAYMOND C. DUDLEY, a citizen of the United States, residing in Chicago, in the county of Cook and State of Illinois, have invented a new and useful Improvement in Car-Roofs, of which the following is a specification.

My invention relates to outside metallic roofs for freight cars; and has for its object 10 the providing of a roof, of said type, that shall be particularly simple of application and flexible or yielding to the weaving of the car in service, and for further objects such other improvements in structure or 15 function as may be found to obtain in the device hereinafter described or claimed.

In the accompanying drawings, forming a part of this specification, and in which like reference numerals indicate like parts 20 in all of the figures,

Figure 1 is a top plan view showing the general construction of the car-roof framework and of the applied metallic outside roof; Fig. 2 is a side elevational view, to 25 show the securing of the transverse caps and sheets at the eaves; Fig. 3 is an enlarged detail section on line 3—3 of Fig. 1, to show the juncture of the caps and sheets at the ridge; Fig. 4 is an enlarged section on 30 line 4—4 of Fig. 1, to show the securing of the transverse caps and sheets at the eaves; Figs. 5 and 6 are enlarged sectional views 35 on the lines 5—5 and 6—6 of Fig. 1, to show the interlocking relation of the transverse caps and sheets; Figs. 7 and 8 are enlarged perspective views of the upper corners of one of the sheets; and Fig. 9 is an 40 enlarged detail plan view to show the mutual overlapping of the ridge caps and transverse caps under each saddle.

10 is the wooden sheathing secured upon the roof-framework formed by the side plates 11, ridge-beam 12, car-lines 13 and purlins 14. The galvanized-iron roofing-sheets 15 overlie the wooden sheathing 10 and extend from the eaves nearly to the ridge-line, each sheet having at its lower end a depending flange 16 that overhangs the fascia 17 and is secured thereto by the 45 nails 18 and clips 19. The other edges of each sheet are free with respect to the wood roof and are retained by only a loose engagement with the overlapping caps at the top and on the sides of the sheet. The sides 50 of each sheet are provided with flanges 20, bent upward and then inward and then re-

bent downward and inward, and adapted to freely and loosely engage and interlock with reversely formed flanges 21 along the sides of the transverse caps 22, which are 55 slipped into such engagement from the eaves ends of said lateral sheet-flanges 20 after the sheets are in place upon the roof. These transverse caps 22 rest freely upon and are longitudinally supported by the 60 wooden filler-strips 23 that extend from the eaves to the ridge-line and are fastened upon the sheathing 10; and said filler-strips are narrow enough, relative to the caps, so that a considerable free space is left 65 between the sides of the strips and the adjacent upturned sheet-flanges 20 with which the caps resting upon the strips are engaged, thus permitting the sheets a considerable lateral movement between the strips, 70 and the caps a similar movement on the filler strips as the roof-frame of the car weaves while the car is in service. The caps have horizontal side portions which extend beyond the filler strips, and are thence bent 75 downward and thence inward so as to have a bearing on the roof sheets to support the side portions of the caps in case the latter should have weight imposed upon them, and are thence bent upward to interlock with 80 the sheet side flanges (Fig. 5). At their outer ends the top members of the transverse caps are bent downward in tongues 24 that overhang the fascia and are secured thereto 85 by spikes 25 and clips 26, thus securing the caps and covering and protecting the eaves end of the inclosed filler-strip and interlocking cap and sheet flanges. The outer 90 side edges of the transverse caps at the ends of the roof are bent down into flanges 27 that overhang the end-fascia 28 and are secured thereto by nails. The top edge of each sheet is provided with a perpendicularly upturned flange 29, to prevent access 95 of water at the ridge, and the said upturned flanges on opposed sheets on opposite sides of the ridge-line are sufficiently separated to permit the free shifting of the sheets as the roof-frame weaves. The sheet 100 corners are left entire at the juncture of the upturned flange 29 with the upturned part of the side-flanges 20 and the spare metal is bent around against the outside of said flange 29, in folds 30, thus stiffening the 105 corners and leaving them water-tight.

The ridge caps 31 are formed with down

wardly bent and outwardly spreading flanges 32 that freely straddle the flanged upper ends of the opposed sheets on opposite sides of the ridge, the outwardly turned lower edges 33 of said ridge-cap flanges 32 pressing lightly upon the sheet-ends within the upturned flanges 29, and so retaining said upper ends of the sheets while not interfering with the free lateral shifting of the sheets 10 as the car-roof weaves. The ends of the top-members of the ridge caps are extended into tongues 34 that mutually overlap and together overlie the tongues 35 into which the upper ends of the top-members of the transverse caps are extended; and these mutually overlapping and underlying tongues 34 and 35 of the intersecting ridge-caps and transverse caps are all provided with the enlarged bolt-holes 36, to freely accommodate the through-bolt 37 that secures to the ridge the saddle 38 that surmounts each cap intersection and rests upon the tops of each pair of opposed transverse caps 22. These enlarged bolt-holes 36, in the tongues 25 of the caps under the saddles, permit the caps 22 and 31 some play as the roof-framework weaves. Running boards 39 are spiked upon and supported by the saddles 38, and hold the said saddles mutually parallel while 30 permitting them some slight swinging play on the bolts 37 that secure the saddles to the ridge. The central running board covers and protects the line of ridge-caps 31.

It is obvious that this outside metal roof 35 may be applied with extreme readiness and without any close adjustment of the several members; and that when applied it will be entirely flexible and yielding to the distortion that the roof-framework necessarily 40 suffers as the car weaves, and yet will come back to normal when the roof-framework is relieved of any distorting strain; and will be at all times a thoroughly efficient and water-proof protection to the wooden roof. 45 The rigid securing of the lower edges of the sheets at fixed positions on the eaves of the car, while the other three edges of each sheet are free save for their loose engagement with the caps and have free space all around 50 them, permits the sheet to shift laterally in response to distortion of the roof-framework and yet insures the return of the sheet to normal position when the distorting strain is removed; and yet the waterproof and other 55 protective features of the metallic roofing are preserved. The movement that occurs, and gives flexibility to the relation between the wood roof and the overlying sheets, may be regarded as a distortion of the wood roof 60 under and free of the body and the upper and lateral edges of each sheet, while the

sheet itself, rigidly secured at the eaves, keeps its place at the eaves and its perpendicularity to the short length of eaves line upon which it is so secured and does not shift 65 along or away from said eaves line or expose any part of said line to the weather; while at the same time the several sheets on either side of the roof may shift in respect to each other if any strain flexes the full eaves line. 70 While the caps hold the body of the sheet down in place and at all times cover its free edges, they do not prevent it from shifting over the roof.

My invention is hereinabove set forth as 75 embodied in one particular form of construction, but such construction may be modified in so far as the subject matter of the claim hereinafter made may be distinguished from prior devices for like purpose.

"I claim:—

In a car roof, in combination: wooden top sheathing, metallic roof sheets formed with upstanding side and ridge flanges, held on the said sheathing and shiftable longitudinally of the car thereon, and spaced apart from each other at their sides and at the ridge; super-carlines arranged between the flanges of the roof sheets and spaced therefrom: transverse seam caps resting at their middle portions on the said super-carlines, and having horizontal extensions beyond the super-carlines and over the flange of the roof sheets and having depending flanges inclosing and interlocking with the side flanges of two sheets, and having their depending flanges spaced from the flanges of the sheets, the said side flanges of the sheets having downward extensions entering between the 100 parts of the flanges of the seam cap, and the seam cap flanges having upward extensions entering between the parts of the flanges of the roof sheet, and formed with flat faces arranged to be brought to bear on the flat 105 portions of the roof sheets to support and brace the said extensions of the seam caps; and ridge caps having flanges inclosing and spaced from the said ridge flanges of the sheets; the eaves edge of the said sheets being 110 fixedly secured to the side of the car to normally maintain and to restore, after flexure of the car, the spacing between the roof sheets and the spacing between the roof sheets and the seam caps.

In testimony whereof, I have hereunto set my hand in the presence of two subscribing witnesses.

RAYMOND C. DUDLEY.
